(57) **CLAIM**

We claim the ornamental design of a skin therapy mask, as shown and described.

DESCRIPTION

FIG. 1 is a back view of a skin therapy mask showing our new design;

FIG. 2 is a bottom view thereof;

FIG. 3 is a front view thereof;

FIG. 4 is a first isometric view thereof;

FIG. 5 is a second isometric view thereof;

FIG. 6 is a left side view thereof;

FIG. 7 is a right side view thereof; and,

FIG. 8 is a top view thereof.
